UNITED STATES PATENT OFFICE.

FRITZ O. VON TOBEL, NOW BY JUDICIAL CHANGE OF NAME MARCELLE JOHN HARDING,
OF NEW YORK, N. Y.

DESIGN FOR A HOLDER FOR A FLAG OR SIMILAR ARTICLE.

54,340.

Specification for Design.

Patented Dec. 23, 1919.

Application filed November 25, 1918. Serial No. 264,112. Term of patent 3½ years.

To all whom it may concern:

Be it known that I, FRITZ O. VON TOBEL, (by decree of court now MARCELLE JOHN HARDING,) a citizen of the Republic of Switzerland, residing at New York, in the county and State of New York, have invented a new, original, and ornamental Design for Holders for Flags or Similar Articles, of which the following is a specification, reference being had to the accompanying drawing, forming part thereof.

The figure is a front elevational view of a holder showing my new design.

I claim:

The ornamental design for a holder for a flag or similar article, as shown.

FRITZ O. VON TOBEL,
By decree of court now Marcelle John Harding.
